UNITED STATES PATENT OFFICE.

SAMUEL STRAUSS, OF LOS ANGELES, CALIFORNIA, ASSIGNOR TO LOS ANGELES TRUST AND SAVINGS BANK, TRUSTEE, OF LOS ANGELES, CALIFORNIA, A CORPORATION OF CALIFORNIA.

SHOE-MACHINE.

1,385,647.

Specification of Letters Patent. Patented July 26, 1921.

Application filed July 22, 1918, Serial No. 246,146. Renewed December 20, 1920. Serial No. 432,139.

To all whom it may concern:

Be it known that I, SAMUEL STRAUSS, a citizen of the United States, residing at Los Angeles, in the county of Los Angeles and 5 State of California, have invented a new and useful Shoe-Machine, of which the following is a specification.

This invention has for one of its principal objects the making of shoes by an inexpensive method.

Another object is to make provision for stretching leather or other suitable upper-forming material over a last so as to shape the leather to the last to form a shoe upper 15 without the necessity of pressing the leather into a female die as has been done heretofore.

Another object is to make provision for basting the upper, thus formed, to the sole 20 of the shoe while the last, upper and sole are held together in the machine so that the upper will retain the shape given it by the machine during the time that elapses between the forming operation and the stitching 25 operation.

Another object is to produce a simple machine that will effect the foregoing objects.

Another object is to produce a machine for simplifying the making of shoes so that 30 labor unskilled in the art of making shoes can be utilized for such work.

Another object is to so construct the last that it forms a guide for cutting the upper that is shaped on it.

35 Other objects and advantages will appear in the subjoined detailed description.

The accompanying drawings illustrate the invention:

Figure 1 is a side elevation partly in vertical midsection of a machine constructed in accordance with the provisions of this invention and capable of performing some of the operations involved in the newly invented method of making shoes. Solid lines 40 show the parts in shoe-forming position and broken lines indicate some of the operating parts in other positions.

Fig. 2 is an end elevation from the left of Fig. 1, the operating handle and upper hand-wheel being indicated in raised positions in broken lines.

Fig. 3 is an enlarged fragmental elevation

mainly in section on line indicated by $\alpha^3-\alpha^3$, Fig. 2.

Fig. 4 is an enlarged detail of one of the 55 devices for detachably fastening the basting collar to its support.

Fig. 5 is a plan section on line indicated by $\alpha^6-\alpha^6$, Fig. 1, the last, leather for forming the upper and the sole being omitted. 60

Fig. 6 is a plan view of the platen, collar for supporting the leather for forming the upper and the standards for supporting the collar, the yoke operating rods being shown in section. 65

Fig. 7 is a plan view of the basting collar.

Fig. 8 is a side elevation of the last.

Fig. 9 is a plan view of Fig. 8.

Fig. 10 is a perspective view of the support and its operating pins. 70

There is provided a last 1 of any suitable construction. In the instance shown in the drawings, see especially Figs. 8 and 9, the last 1 is provided with an annular groove 2 at the ankle portion and a groove 3 extending longitudinally from the groove 2 toward the toe of the last. The last 1 is merely typical of a variety of lasts which may be used. The last forms a portion of the machine and constitutes a portion of the invention. 75

There is provided a last 1 of any suitable construction. In the instance shown in the drawings, see especially Figs. 8 and 9, the last 1 is provided with an annular groove 2 at the ankle portion and a groove 3 extending longitudinally from the groove 2 toward the toe of the last. The last 1 is merely typical of a variety of lasts which may be used. The last forms a portion of the machine and constitutes a portion of the invention. The reason that the machine will not function without the last to operate on the material of which the shoe is to be made. The last 1 is adapted to rest on a sole indicated at 4 in Figs. 1 and 3. The sole is 80 formed of leather or other suitable material and does not form a portion of the machine. The sole 4 rests on a platen 5 which is preferably provided with upwardly projecting pointed pins or spurs 6 adapted to penetrate the sole so as to hold the sole against lateral movement. The upper face of the platen 5 may be curved as clearly shown in Fig. 1 so as to conform in shape with the curved bottom of the last. 85

Means are provided to lower and raise the platen 5 and such means may be variously constructed and in the drawings the construction is as follows: The platen 5 has a downwardly extending boss 7 which is provided with a socket 8 to detachably receive the upper end of a screw 9, thus different sizes of platens 5 may be readily mounted on the upper end of the screw 9. The screw 95

100

9 has its lower end journaled in a bearing 10 of a frame indicated in general by the character 11, the bearing 10 being fastened by screws 12 or the like to the under side of 5 a cross-bar 13 of the frame. Surrounding the screw 9 and resting upon the crossbar 13 is a bevel gear wheel 14 provided with a pin 15 which engages and thrusts against the threads of the screw so that when the 10 bevel gear 14 is turned it will cause endwise movement of the screw 9 in a manner easily understood. To turn the bevel gear 14 said gear meshes with a bevel pinion 16 on a shaft 17 which is journaled in bearings 15 18, 19 formed by portions of the frame 11. The shaft 17 may be driven either manually or by mechanical power of any suitable description. In this instance the shaft 17 is provided with a hand-wheel 20 whereby said 20 shaft may be turned so as to effect raising and lowering of the last 1.

When the platen 5 is in raised position, as shown in full lines in Fig. 1, it is accommodated in an opening 21 which extends 25 through a collar 22 provided at its opposite ends with lugs 23 that are detachably mounted on and fit in grooves 24 of standards 25, said standards forming portions of the frame 11. The collar 22 is typical of various sizes 30 of collars which may be used if desired and may be readily interchanged with one another according to the size of shoe it is desired to make.

A piece of leather, which is to form the 35 upper of the shoe, is indicated in dotted lines at *a*, Fig. 1, and is adapted to be placed over the opening 21 in the collar 22, and means are provided to hold the piece of leather in position on the collar and such 40 means will now be described: Above the collar 22 is a yoke 26 having an opening 27 sufficiently large to accommodate the last 1. This yoke 26 is adapted to be brought into engagement with a bead 28 on the collar 22, 45 the bead extending around the opening 21. It is clear that when the marginal portion of the piece of leather *a* rests on the bead 28 and the yoke 26 rests on the marginal portion of the leather the leather will be held securely and will extend across the opening 50 21. The yoke 26 is shiftably mounted so that it can be raised and lowered and for this purpose the ends of the yoke are provided with holes 29 to accommodate vertically extending rods 30, there being shoulders 31 on the rods normally engaging the under-face of the yoke 26 so as to support said yoke.

Any suitable means may be provided for 60 producing endwise motion of the rods 30 and in the instance shown in the drawings said means are constructed as follows: The rods 30 are pivoted at 32 to arms 33 which in turn are pivoted at 34 to cranks 35 on 65 the opposite ends of a rockshaft 36 that is

journaled in bearings 37 fastened to the underside of the crossbar 13 and formed by portions of the frame 11. Collars 38 may be provided on the shaft 36, fastened in place by set screws 39, or their equivalents, 70 to prevent endwise movement of the shaft 36, said collars thrusting against the bearings 37. One of the cranks 35 is provided with an extension forming a handle 40 whereby operation of said crank is effected so as to 75 rock the shaft 36 and cause movement of the other crank to correspond. When the cranks 35 are swung in this fashion they cause movement of the arms 33 so as to produce endwise motion of the rods 30. From 80 the drawings, it is clear that when the handle 40 is up, as indicated in broken lines in Fig. 2, the yoke 26 is in raised position, whereas, when the handle 40 is down as shown in solid lines in said figure, the yoke is in its lowered 85 position for clamping the leather, which is to form the upper, onto the collar 22. The yoke 26 is normally held on the shoulders 31 against the reaction pressure of the collar 22 by any suitable means, preferably such 90 means being more or less resilient. For this purpose the upper end portions of the rods 30 may be inserted through resilient members 41 of any suitable character. In the drawings the resilient members 41 are shown 95 in the form of soft rubber bushings, and washers 42, 43 are placed at the ends of the rubber bushings 41, and nuts 44 are screwed on the outer ends of the rods 30 against the washers 42 to hold the rubber bushings 41 100 against upward movement. The utility of this particular construction will be made clear hereinafter.

The yoke 26 is provided with an endless recess or groove 45 in its under face close 105 to the opening 27 and shiftably mounted in said groove is a basting collar support in the form of an irregular ring 46. This support 46 forms an operating member for a basting collar 47 which is detachably connected to the support 46 by any suitable means. These means may be constructed as shown in the drawings as follows: The support 46 is provided at opposite ends with flat downwardly extending springs 48 adapted to be accommodated in notches 49 in the ends of the collar 47. The springs 48 frictionally engage the collar 47 and said springs may have their free ends bent inward as at 50 so as to further insure against accidental displacement of the collar 47 from the support 46. If the collar 47 be pulled downward it will be released so that it can be readily removed from the machine. The support 46 is normally held upward in the 110 groove 45 and for this purpose said support is provided with upwardly projecting pins 51 which extend through the yoke 26 and above the upper face thereof. The pins 51 are provided with shoulders or abutments 115

52 between which and the upper face of the yoke 26 are inserted coil springs 53 which function to normally force the pins 51 upward so as to hold the support 46 and collar 47 retracted in the recess 45.

5 Means are provided to force the pins 51 downward so as to move the support 46 downward and such means may be variously constructed. Appropriate means for pressing the pins 51 downward are shown in the drawings and are constructed as follows: The upper ends of the pins 51 are adapted to be engaged by an operating member 54 in the form of a plate which is adjustably suspended by a screw 55 threaded through a standard 56 mounted on the yoke 26. The plate 54 may be provided at its ends with notches 57 to accommodate the legs 58 of the standard 56 so that the plate 54 will be guided and held against lateral movement when it is being raised and lowered. Any suitable means may be provided to turn the screw 55 and such means may be mechanical power or may be manually operated. In the drawings, I have shown for this purpose a hand-wheel 59 mounted on the upper end of the screw 55 and it is clear that turning of the hand-wheel will cause raising and lowering of the plate 54. The collar 47 is provided with downwardly projecting basting members in the form of sharpened pins or spurs 60 arranged at intervals and it is clear that when the hand-wheel 59 is turned in the appropriate direction to lower the plate 54 the basting members 60 will be caused to penetrate the piece of leather forming the upper of the shoe and pass into the sole 4. To avoid blunting of the points of the basting members 60 a recess or groove 61 is provided in the platen 5 in position to register with the basting members as clearly shown in Fig. 3 of the drawings. Thus sufficient pressure may be brought to bear on the pins 51 by the plate 54 to drive the basting members 60 completely through the sole 4 so as to baste the piece of leather forming the upper to the sole.

It now appears that, when the basting collar 47 has been forced downward against the piece of leather forming the upper of the shoe, further pressure would be liable to cause breakage of some of the parts of the machine, and that because of the provision of the resilient members 41 said members 41 will be compressed somewhat if the pressure is continued after the basting members have been driven home. As soon as the operator notes that the resilient members 41 are beginning to be compressed, he will cease turning the hand-wheel 59 as such compression will denote that the basting members have been driven home and that further pressure is unnecessary.

It may be desirable to loosen the sole 4 from the spurs 6 before removing the shoe

upper and sole together with the last from the machine in order to avoid any liability of prematurely loosening the upper from the sole when so removing them, and for this purpose the platen 5 may be provided with perforations 62 through which any suitable tool may be inserted to press the sole upward together with the shoe upper and the last. This will of course be done after the yoke 26 has been moved to its raised position.

The rods 30 are shiftably mounted in upper and lower guides or bearings 63, 64 of the frame 11, said guides projecting outward from the standards 25.

In practice, to make a shoe by the use of the above described machine, I proceed as follows: I first see that the platen is in the lowered position indicated in broken lines in Fig. 1, that the plate 54 is in raised position as also indicated in broken lines in Fig. 1, and that the yoke 26 is in raised position. A piece of leather or other suitable material for forming the sole 4 of the shoe is cut into the desired shape and size and is placed on the platen 5 and pressed downward thereon so that the spurs 6 will penetrate the sole 4 and firmly hold it against slippage on the platen. Then the last 1 will be placed in position on the sole 4.

Then the piece of leather indicated in dotted lines at α , which is to form the upper of the shoe, is placed in position over the opening 21 and the handle 40 is lowered to hold said piece of leather in position. Then the operator will turn the hand-wheel 20 to move the platen and the sole and last upward to bring the last into engagement with the piece of leather α . The operator will continue to turn the hand-wheel 20 to stretch the leather over the last 1, the last being forced upward until the marginal portion of the sole meets the flange 65 of the shoe upper 66 as clearly shown in Fig. 3. During this pressing movement the last 1 is projected into the opening 27 and the piece of leather forming the upper 66 is not held in any place excepting by its flange 65. This allows the leather to be stretched evenly and smoothly over the last so as to give the upper the true and exact shape of the last.

Then the operator will turn the hand-wheel 59 to move the plate 54 downward so as to cause the support 46 and its collar 47 to move downward toward the flange 65 of the upper and thereby force the basting members 60 through the flange 65 and through the sole 4 to baste the sole and upper together. After this is accomplished the operator will turn the hand-wheel 59 in the appropriate direction to retract the plate 54 and the pressure of the springs 53 will then become operative to raise the pins 51 and consequently the support 46. Owing to the basting members 60 holding the basting collar 47 to the upper 66 of the shoe, and the upper being

held by the collar and yoke 22, 26, the springs 48 will yield so that the basting collar 47 will become detached from its support 46.

The operator then raises the handle 40 so as to release the flange 65 of the upper 66, which has been formed, from pressure of the yoke 26 and he will, if necessary or desirable, insert a suitable tool in the holes 62 so as to force the sole 4 loose from the platen 10 5. The sole 4, upper 66, basting collar 47 and the last 1 will then be removed together from the machine and the flange 65 and the sole will be stitched together in a manner well understood in the art. It is clear that 15 the basting collar 47 forms a guide for the stitcher so that the stitches can be accurately placed.

After the stitching operation is effected, the operator cuts the upper 66 adjacent the 20 ankle portion of said upper so as to form the opening through which the wearer's foot is inserted in the shoe. In thus cutting the upper, the groove 2 in the last forms a guide for the knife-blade so that a person inexperienced in the shoe making art can cut the 25 upper correctly. The operator will also cut a slit in the shoe, his knife being guided by the groove 3 in the last. The shoe is then finished in any well-known manner, the buttons or eyelets being placed in position and the edges of the opening being stitched to 30 35 finish them off.

In the foregoing description of making the shoe no mention is made of a lining therefor but it is clear that if it is desired to incorporate a lining in the shoe, the lining will be placed in position beneath the piece of leather which is to form the upper and then the foregoing described operations will be 40 carried out so that the lining will be formed, basted in place, and afterward stitched in place to form a portion of the shoe as is readily understood.

It may be desirable in some instances to 45 hold the handle 40 in its raised position as indicated in dotted lines in Fig. 2 and for that purpose I have provided a resilient latch member 67 fastened at one end to the frame 11 and provided at its free end with a detent 50 55 68 adapted to be normally projected into the path of travel of the handle 40 by reason of the resiliency of the member 67. When the handle 40 is in raised position the forward edge thereof is engaged by the rear face of the detent 68 so that the handle 40 cannot be lowered until the detent is pushed to one side.

In the above description and the claims 60 wherever the term "leather" is employed it is to be understood that the term "leather" defines not only the hides of animals but any natural or manufactured material that can be shaped into shoes by the use of the described machine.

65 It is understood that the invention is not

limited in all of its phases to the exact construction shown in the drawings and described above but that the invention also includes such modifications and changes as lie within the spirit and scope of the appended claims.

I claim:

1. A shoe machine comprising a platen, a last adapted to be positioned on a sole resting on the platen, a collar, means to hold a piece of leather on the collar, and means to produce relative movement of the collar and platen toward one another to stretch the leather over the last.

2. A shoe machine comprising a platen, a last adapted to be positioned on a sole resting on the platen, a collar, means to hold a piece of leather on the collar, means to produce relative movement of the collar and platen toward one another to stretch the leather over the last, a basting collar above the platen provided with basting members, and means to produce relative movement between the platen and basting collar to force the basting members toward the platen.

3. A shoe machine comprising a platen, a last adapted to be positioned on a sole resting on the platen, a collar, a yoke above the collar, means to produce relative movement of the yoke and collar toward one another to hold a piece of leather therebetween, means to produce relative movement of the collar and platen toward one another to stretch the leather over the last, a support shiftably mounted on the yoke, means to move the support toward the platen and relative to the yoke, and a basting collar detachably fastened to the support and provided with downwardly projecting basting members.

4. A shoe machine comprising means to hold a piece of leather, a last, and means including a sole-supporting platen to produce relative movement of the leather holding means and last toward one another to stretch the leather over the last to form an upper.

5. A shoe machine comprising means to hold a piece of leather, a last, means including a sole-supporting platen to produce relative movement of the leather holding means and last toward one another to stretch the leather over the last to form an upper, and means to fasten a sole to the upper while the upper is held.

6. A shoe machine comprising means to hold a piece of leather, a last, means to produce relative movement of the leather holding means and last toward one another to stretch the leather over the last to form an upper, a basting collar having basting members projecting therefrom, and means to force the basting collar toward the leather holding means.

7. A shoe machine comprising a platen

- adapted to support a sole, a last adapted to rest on the sole, a collar, means to hold a piece of leather on the collar, and means to raise the platen to force the last through the collar to shape the leather to the last.
8. A shoe machine comprising a platen adapted to support a sole, a last adapted to rest on the sole, a collar, means to hold a piece of leather on the collar, means to raise the platen to force the last through the collar to shape the leather to the last, and means to fasten the marginal portions of said leather to the sole while the leather is in the holding means.
15. 9. A shoe machine comprising a platen adapted to support a sole, a last adapted to rest on the sole, a collar, means to hold a piece of leather on the collar, means to raise the platen to force the last through the collar to shape the leather to the last to form an upper, a basting collar having basting members projecting therefrom, and means to force the basting collar toward the sole to baste the upper and sole together.
- 20 10. In a shoe machine, the combination with sole supporting means, of means to
- shape an upper, and means including a detachable basting collar to fasten the upper and sole together.
11. In a shoe machine, the combination of means to shape an upper, and means including a detachable basting collar to fasten a sole to the upper.
12. In a shoe machine, the combination with sole-supporting means, of a last above the sole-supporting means, and means including a detachable basting collar to baste the sole to an upper on the last.
13. In a shoe machine, the combination with sole supporting means, of means to shape an upper and to hold the upper and sole toward one another, and means including a detachable basting collar to fasten the upper and sole together while they are so held.

Signed at Los Angeles, California, this 5th day of June, 1918.

SAMUEL STRAUSS.
